WALL PLATE OR SIMILAR ARTICLE

Louis Ludwig, New York, N. Y.

Application November 8, 1951, Serial No. 17,328

Term of patent 14 years

(Cl. D26—13)

To all whom it may concern:

Be it known that I, Louis Ludwig, a citizen of the United States, residing at 310 E. 44th St., in the county of New York and State of New York, have invented a new, original, and ornamental Design for Wall Plate or Similar Article, of which the following is a specification, reference being had to the accompanying drawing, forming part thereof.

In the drawing

Fig. 1 is a front view of a wall plate showing my new design, and Figs. 2 and 3 are top and side views, respectively, of said plate.

I claim:

The ornamental design for a wall plate or similar article, substantially as shown.

LOUIS LUDWIG.
